UNITED STATES PATENT OFFICE.

ROBERT J. MAGOR, OF PASSAIC, NEW JERSEY.

CAR.

1,080,709.

Specification of Letters Patent.

Patented Dec. 9, 1913.

Application filed April 22, 1913. Serial No. 762,994.

To all whom it may concern:

Be it known that I, ROBERT J. MAGOR, a subject of the King of Great Britain, and a resident of the city of Passaic, in the State of New Jersey, have invented an Improvement in Cars, of which the following description, in connection with the accompanying drawings, is a specification, like letters on the drawings representing like parts.

10 The present invention relates to cane cars and has to do especially with fastening means for the upright stakes or posts comprising the load retaining sides.

The object here in view is to provide a 15 more efficient fastening means or socket for the said stakes than those which are now and have hitherto been used. Such devices have been entirely ineffective to keep the stakes in rigid vertical alinement, a 20 condition difficult to maintain owing to the fact that cane cars, in order that they may readily be loaded from above, are constructed without roofs or other bracing means for the stakes.

25 Generally, in unloading, one end of the car is tilted upward and the cane is discharged through a door at the other end the frame of which is kept rigid by a transverse sill. Obviously, it is essential to practical dumping that the transverse thickness

30 of the load of cane be not substantially greater than the opening in the door-frame. Therefore, if the stakes sag outwardly they will permit the load to bulge and consequently block the discharge opening.

35 Wooden stakes have been found to be impracticable not alone on account of their tendency to bend but also because of frequent breakage, so that it is generally preferred to use ribbed iron stakes. The difficulty with respect to the latter, however, is to provide stake retaining pockets accurately fitted to the metallic stakes and to maintain this condition during continued 40 use. These sockets, or pockets as they are commonly known in the car art, are generally made either of cast iron or pressed steel; and when a metallic stake is used, an absolutely perfect fit must be had between the stake and pocket if the former is to be 45 maintained in a vertical position at all times by the pocket. Such exact fitting not only requires expensive and careful machining in the first instance, but even such 50 fitting will accomplish little toward the end

in view when the cars are shipped, as is commonly the case with cane cars, before the stakes are assembled or placed in position in their pockets. It will be understood that where cane cars are sent to the tropics, 60 it is quite essential that they be collapsed so as to be shipped as flatly and as compactly as possible. It accordingly becomes necessary for the user of the cars to assemble the stakes in their proper positions upon the 65 cars when he receives them. Moreover, even if the stakes are accurately fitted to the pockets in the first instance, the latter, particularly when made of pressed steel, soon 70 become bent and deformed under the forces 75 imparted through the stakes when the car is in use. It thus happens that the old metallic pockets are entirely impracticable for use in cane cars, under the conditions specified.

For the purpose of overcoming such difficulties as have been outlined above, the herein described stake fastening means has been devised wherein the stakes are maintained in vertical alinement by their fastening means and thus permit the load to be dumped without choking the discharge opening.

The improvement is shown in the accompanying drawing of which—

Figure 1 is a perspective view of a sufficient portion of a car embodying the improvement to illustrate the same, and Fig. 2 is an enlarged detail view of one of the fastening means applied to the side of the 90 car with the stake omitted, as said device would appear looking down upon the same.

Referring to the drawings, a pair of plates *a* adapted to conform substantially to the flange on the stake *b* are secured to the side 95 member *c* of a cane car by rivets or bolts *d*. The stake *b*, here shown as T-shaped, is slid into the openings between the said angle plates and is fastened there by means of bolts, or other suitable fastening means, *e*. 100 The angle plates *a*, in addition to being deformed to conform substantially to the shape of the stakes, are so made that when fastened to the side sill of the car, their free sides *f* diverge more or less, as shown in Fig. 2. Thus, when these sides are drawn together about the stake by the fastening means *e*, their corner portions or shoulders *g* will press inwardly against the flange of the 110 stake and hold it tightly against the side of

the car. It will be obvious that in this way the plates *a* may be made to bind the stake to the side of the car with great pressure.

While the particular form or shape of the stakes is immaterial, it will be noted that each stake should have a rib and a flange, the former being arranged substantially at right angles to the side plane of the car to take up the strain within the stake caused by the load, and the latter resting flatly against the side of the car to form a base for maintaining the stake in a vertical position. While the present case shows the use of a T-iron stake, it is obvious that other forms such as angles or I-beams may be employed equally as well.

It may be pointed out that the present stake fastening means not only takes up less room itself than the original stake pockets, and hence makes the car floor more compact for shipping, but it is also much better able to resist hard usage to which it will be invariably subjected. A great many of the old stake pockets used to get badly bent in handling the cars in railroad yards and on steamship docks. It will be understood that the present improvements may be applied to all kinds of cars as well as to cane cars.

I claim as my invention:

1. In a car, the combination with a stake having a flange and a rib, of a fastening de-

vice therefor comprising a pair of angles each having one side fixed to the car and their other sides embracing said rib with the corner portion of at least one of said angles pressed in against said flange.

2. In a car, the combination with a stake having a flange and a rib, of a fastening device comprising a pair of angles deformed to fit substantially around the flange and embrace the rib, means to secure one side of each angle to the car, and means to draw the other sides of the angles together about the rib, the last named sides diverging before being drawn together whereby the corner portions of the angles may be forced inwardly during fastening.

3. In a car, the combination of a T-shaped stake, angle plates secured to the side member of the car, the fixed sides of said angle plates being deformed to fit the flange of the stake and the free sides embracing the rib of the stake, and a fastening member passing through said free sides and said rib.

In testimony whereof, I have signed my name to this specification, in the presence of two subscribing witnesses, this 22nd day of April, 1913.

ROBERT J. MAGOR.
